CARD HOLDING ATTACHMENT FOR WRITING MACHINES

Herman Mieth, Louisville, Ky.

Application December 27, 1938, Serial No. 247,979

3 Claims. (Cl. 197—135)

The invention relates to improvements in card-holding devices for writing machines controlled by a holding attachment in combination with the platen roll, and the objects of the improvement are, to provide a holder for cards on the platen roll which is stationary and independent of the turning of the platen roll and which facilitates the movement of the card in spacing and writing to the full extent of the card, which may be heavy or light.

One form of the invention is illustrated in the accompanying drawing, in which Figure 1 is an elevational view of the device as it appears on the typewriter. The whole arrangement is held and adjusted backward or forward as illustrated in Figure 1 where 16 is a bushed loop for fastening to the back of the machine 4 and 15 loops over the back cross rod 5a, the screw action adjusts the card holder 7 up or down. The card holder 7 is held by the cross rod 6 and may be raised or lowered from the platen roll and actuated by the arms 12b and 13b and the helical extension springs, 12c, 12d and 13c, 13d, as illustrated in Figs. 2 and 3. The small holes in 7 are for adjusting the card for close writing. The arms 12b and 13b have extension tubes for carrying the rod 6. 11 and 12 represent the adjusted holding plates.

Figures 2 and 3 show the holding plates, where Figure 2 is for the platen roll end shafts and Figure 3 direct on the full perimeter of the platen roll, in which both Figures 2 and 3 have the same action. Both may be pressed down for adjustment, or better in combination with the lever 12a and 13a where 12c and 13c pries the plates 12 and 13 apart on the swivel pin 5 and 5a, better illustrated in Figure 4, and drawn together by the spiral spring 12c, the most flexible of springs and thus creating a positive effect. The swivel pins 5 and 5a are the extension of the cross holding rods 5 and 5a.

Figure 6 represents the card holder where 7 is the plate on which 6 is set and through which the rod 6 passes and on which the card holder revolves, this in turn is actuated by the arms 12b and 13b as shown in Figures 2 and 3. Just before the rollers 8 the plate 7 has a slight offset which throws the card or paper directly under the rollers 8, facilitating its forward movement.

Figure 7 represents elevational view of the side of the bushed loop 16 as shown on the adjusting rod 14, Figure 5, and is adjustable on 14 by a screw action, and to protect machine enamel it is bushed by a soft material as felt or leather.

I claim:

1. In a card-holding attachment for writing machines provided with a carriage and a platen mounted therein,—a pair of detachable, hinged clamping plates attachable at each end of the 5 platen; springs for holding each pair of clamping plates in operative position with respect to the platen; cross-rods for holding said clamping plates in spaced relation axially of the platen; a spring-pressed bail member mounted on 10 the clamping plates; a paper pressing plate, having multiple rollers thereon and observation holes therein, slidably mounted on said bail member and designed to press against the platen to hold a card to be written upon; and adjustable rod-members removably mounted for connecting one of the cross-rods and the platen-carriage to retain the device in its card-holding position.

2. A card-holding attachment for writing machines having a carriage and a platen; said attachment comprising,—a pair of detachable clamping plates, operative with jaws, fixed at either end of the platen; a lever operatively installed between each pair of said plates and adapted to open the jaws thereof; parallel cross-rods designed to hold said plates parallel with other and spaced relatively to said plates; helical extension springs on each pair of said plates, designed to hold the jaws thereof in their service position; a spring-pressed swinging arm mounted on a pintle hinge on the inner side of each pair of clamping plates; a cylindrical socket rigidly installed in the inner lower position of each of said spring-pressed swinging arms; a 35 round rod having its opposite ends loosely and securely installed in said sockets; a paper-pressing plate with observation holes therein, slidably mounted on said round rod and adapted to press against the platen to hold a card thereto to be 40 written upon; and adjustable means for removably connecting one of said cross-rods with the carriage of the platen for holding said attachment in its operating position on the writing machine.

3. In a card-holding attachment, of the character described, for writing machines provided with a carriage and a platen mounted therein,—a pair of hinged installation-plates consisting of operative jaws detachably set on and about 50 the platen at each end thereof and designed to hold said attachment in a service alignment with respect to said platen; rigid means for holding said installation-plates parallel with each other and spaced in longitudinal relation to the platen; 55

hinged means for conveniently opening the jaws of said installation-plates for attaching said card-holding device to said writing machines and for detaching the same therefrom; extension-springs on said jaws for automatically closing the jaws to hold said installation-plates in their service position on and about said platen; a spring-pressed bail mounted on the inner sides of said installation-plates; a paper-retaining

plate slidingly installed on said bail and designed to press against said platen to hold a card securely to be written upon; observation-perforations made through said paper-retaining plate to aid an operator in adjusting his card for writing thereon; and adjustable and detachable means for connecting the card-holding attachment to the carriage of the platen.

HERMAN MIETH.
